A. T. CONNELLY

COMBINED CONTAINER AND DISPLAY TRAY

Filed July 13, 1922

UNITED STATES PATENT OFFICE.

ARTHUR T. CONNELLY, OF AUBURNDALE, MASSACHUSETTS, ASSIGNOR TO UNITED DRUG COMPANY, OF BOSTON, MASSACHUSETTS, A CORPORATION.

COMBINED CONTAINER AND DISPLAY TRAY.

Application filed July 13, 1922. Serial No. 574,767.

This invention relates to combined containers and display trays and with regard to certain more specific features thereof to such devices for use in the storage of so-called bulk confectionery according to improved methods of merchandising such bulk confectionery.

It has recently come to be a practice in the sale and transportation of bulk candy to assemble a multiplicity of inexpensively packaged units in a large container holding possibly five, six, ten, or twenty-five pounds of confectionery. Under these conditions the cover of each of the top layer of packages has been removed and the packages set up in display position. One of the difficulties encountered in this method of displaying merchandise is that as the packages are sold the display level recedes to the interior of the box where the prominence of the display is to some extent modified. Another objection is that the dispenser is obliged to remove one of the display boxes in order to get at the remainder of the stock and then return the display package to position.

The present invention has for its object the provision of very inexpensive and simple means for supporting a number of packages in display position in a container or storage pocket from which similar packages may be quickly and conveniently removed for sale. Other objects will be in part obvious and in part pointed out particularly hereinafter.

The invention accordingly consists in the various features of construction, combination of elements and arrangements of parts, which will be exemplified by the construction hereinafter set forth and the scope of the application of which will be indicated by the appended claims.

Referring now to the drawing wherein is shown one of various possible embodiments of the invention:

Fig. 1 is a plan view of my combined storage and display device.

Fig. 2 is a view in vertical central section of the display device shown in Fig. 1, illustrated with the packages in positions of storage and display as in actual use.

Referring now more particularly to the drawing, a container body is shown as consisting of the base 10, upstanding side walls 11 and 12, front wall 13 and a connecting member, or strut, 14, which joins the two upstanding side walls at the rear of the con-

tainer body. This combined storage and display device has been devised particularly with the idea of providing a combined display and storage capacity which shall be equal to the capacity of the original carton, or box, in which the so-called bulk confectionery is shipped. For example, in connection with the present illustrative embodiment, it will be noted that there are twelve packages. Each one of these packages is put up according to definite weight, size and shape. The weight of each package is some fixed aliquot factor of the aggregate weight of all the packages. As for example, if the aggregate weight is six pounds, each package has a weight of one-half pound. The size of the packages is such that they may be arranged in the original shipping carton in three stacks, four packages to a stack packed snugly to completely fill the shipping container. Then according to the present embodiment of the invention, if three of the packages are arranged in the display portion of the container, the remainder of the packages may be introduced through the open rear end of the container and arranged as shown in Fig. 2. I, therefore, construct the side upstanding walls with top edges which slope upwardly from the front wall of the box toward the rear. To each side wall I fix an angle member 13^a extending in parallelism with the top edge of the wall and in opposed relation to each other. One face of each angle member serves as a means for securing the same to its side wall and the other face of each angle member projects inwardly constituting a shelf upon which the individual packages may be supported in inclined fashion. Periodically portions of the angle members are turned in to provide opposed stops 14^a serving as points of registration for the front wall of the packages.

This invention has particular application in carrying out a new idea of merchandising so-called bulk confectionery, which idea, as hereinbefore briefly explained, involves the packaging of confectionery in inexpensive fractional weight units, each one of which is an aliquot factor of the total weight of all the packages. Inasmuch as the size and weight of the different pieces of confectionery vary over a substantial range, it is necessary at times to increase the height of the package and sometimes the width. The length, however, is maintained substantially

uniform. For this reason the angle members are arranged suitably below the top edges of the upstanding side walls and the stops 14^a permit variation in the widthwise dimension of the packages without destroying the appearance of uniformity in arrangement. Each package is constructed with a cover 15 which, for display purposes, is removed and telescoped with the base of 10 the box 16. When the packages have been arranged in display position, a glass plate 17 is laid in over the boxes and is held against displacement by the extending portions of the side and front walls. Where 15 it is necessary, on account of the size or weight of the confectionery, to arrange the same in a deeper box, the present display apparatus readily adjusts itself to such variation in dimension. It will also be seen from 20 inspection of Fig. 2 that the box may be made with a wide range of variation widthwise without destroying the uniform appearance of the displayed merchandise. With the packages arranged in the display 25 chamber all of the remaining packages which were shipped in the original carton may be located in the storage chamber below, as shown clearly in Fig. 2, and these are accessible for delivery by reason of the fact 30 that the container is open at the rear end. The front wall is constructed with upper and lower clips 20 constituting means for holding a card of printed matter and the cross strut 14 is provided with clips 21 providing for the removable mounting of a display card.

Having described the invention, what I claim is:

- 40 1. In a storage and display device, a container body having front, bottom and side walls with open top and back, an angle member attached to the inner side of each side wall near the top edge of the said side wall, and inwardly turned stops on the said angle members.
- 45 2. In a storage and display device, a container body having front, bottom and side walls with open top and back, an angle member attached to the inner side of each side wall near the top edge of the said side wall and inclined upwardly from the front of the body toward the rear, and inwardly turned stops on the said angle members.
- 50 3. In a storage and display device, a container body having front, bottom and side walls with open top and back, an angle member attached to the inner side of each side wall near the top edge of the said side wall and inclined upwardly from the front of the body toward the rear, and inwardly turned stops on the said angle members.
- 55 4. In a storage and display device, a container body having front, bottom and side walls with open top and back, an angle member attached to the inner side of each side

wall near the top edge of the said side wall and inwardly turned and opposed stops on the said angle members.

60

4. In a storage and display device, a container body having front, bottom and side walls with open top and back, an angle member attached to the inner side of each side wall near the top edge of the said side wall, and inclined upwardly from the front of the body toward the rear, and inwardly turned and opposed stops on the said angle members.

65

5. In a storage and display device, a container body having front, bottom and side walls with open top and back, an angle member attached by its upper leg to the inner side of each side wall near the top edge of the said side wall and inclined upwardly from the front of the body toward the rear, the lower leg of the said angle member extending inwardly at right angles to the side wall, and angular stops extending inwardly from the upper legs of each of the said angle members and above the lower leg thereof.

70

6. In a storage and display device, a container body having front, bottom and side walls with open top and back, an angle member attached by its upper leg to the inner side of each side wall near the top edge of the said side wall and inclined upwardly from the front of the body toward the rear, the lower leg of the said angle member extending inwardly at right angles to the side wall, and angular stops arranged in opposed pairs and extending inwardly from the upper legs of each of the said angle members and above the lower leg thereof.

75

7. In a storage and display device, a container body having front, bottom and side walls with open top and back, an angle member attached by its upper leg to the inner side of each side wall near the top edge of the said side wall and inclined upwardly from the front of the body toward the rear, the lower leg of the said angle member extending inwardly at right angles to the side wall, angular stops arranged in opposed pairs and extending inwardly from the upper legs of each of the said angle members and above the lower leg thereof, and a strut connecting the upper portions of the rear of the side walls, the upper portions of the front wall, side walls and the strut cooperating with the said lower legs of the angle members in forming an enclosure for holding a series of packages therein.
